CORNER JOINT STRUCTURE FOR
KNOCKDOWN BOXES

Paul L. Von Canon, West End, N. C.

Application November 22, 1946, Serial No. 711,567

2 Claims. (Cl. 217—65)

1

My invention has for its object to provide a method of constructing rectangular wooden frames suitable for making boxes or drawers for furniture whereby such articles may be fabricated in knockdown form and readily assembled.

My invention also comprehends the design of complementary interlocking joints at the diagonal corners of a box or drawer frame which may be interconnected by a relative rotary movement of the side pieces of the box when their ends are first brought together in angular position and one of them is rotated into a position of 90° with respect to the other.

Another feature of my invention is the provision of two complementary joints of different forms respectively located at diagonal corners of the box frame each comprising interlocking tongues and grooves which when the ends of the four side pieces of the box are placed together rhomboidally interengage when said pieces are simultaneously adjusted into rectangular position.

A still further object of the invention is to provide forms of joints which may be used in duplicate for effecting connection between the forward ends of drawer side pieces and the drawer front which will both cheapen and improve the construction of furniture drawers per se.

To these and other ends my invention embodies further improvements all of which will be fully described in the accompanying specification, the novel features thereof being set forth in the appended claims.

In the drawings:

Figure 1 is a plan view of a box or drawer frame in which the four sides are connected in accordance with the method comprising my invention.

Figure 2 is a view illustrating the form of framing joints employed in carrying out my invention and the method of interlocking the four corners of a box or drawer.

Figure 3 is a side elevation showing a drawer with the bottom attached which permanently secures the side pieces in their assembled position.

Figures 4 and 5 are fragmentary views illustrating the assembly of furniture drawer side pieces and the drawer front embodying the two forms of framing joints, the former showing the joint requiring the side pieces to be revolved outwardly and the other in which the side pieces are secured in position by rotating their free ends in a direction inwardly or toward each other.

Figure 6 is a detail of the end piece showing its attachment to the free ends of drawer side

2

pieces for holding the latter in locked position.

Similar reference characters in the several figures indicate similar parts.

In the construction of certain types of boxes and especially drawers for furniture, it is often desirable to finish the several pieces which compose the completed article at the mill and assemble them at other points. To facilitate their manufacture and assure that when the several side pieces are brought together in final form they will fit precisely to form a perfectly rectangular structure, I have provided unique forms of complementary joints which are adapted to interlock at the four corners when the several side pieces are brought together by a relative rotary movement which is effected in a single operation.

In order to illustrate my invention I have shown in Fig. 1 a rectangular frame comprising the side pieces 1 and 2 and end pieces 3 and 4.

These were assembled by first placing them with their beveled or mitered ends in juxtaposition to form a rhomboid as shown in Fig. 2, and subsequently straightening up this geometrical figure so that the adjoining ends of the several pieces are each at right angles.

The interlocking of the several corners is accomplished by providing the diagonal corners with two different pairs of joints generally comprising interengaging tongues and grooves formed in conjunction with the mitered faces on the ends of the four side pieces of the box or drawer.

At two of the opposed corners, indicated by *a* and *b* it will be observed that when the ends of the side and end pieces are brought into juxtaposition at an angle to each other the mitered faces 5 and 6 and 7 and 8 engage at their inner points, forming angles which diverge outwardly. Likewise the mitered faces 9—10 and 11—12 at the remaining corners *c* and *d* engage at their outer points forming converging angles.

At the corners *a* and *b* I form on one of the inner faces such as 5 and 8 tongues 13 and 14 and on the other faces grooves 15 and 16, said tongues and grooves each having their shoulder portions curved, thus forming on the tongues undercuts and on inner sides of the grooves shoulders 17 fitting therein when one side is rotated relative to its adjoining pieces and serving to prevent pulling them apart. The peripheries of the tongues and the bottoms of the grooves are crowned so as to fit neatly one within the other to provide close fitting surfaces.

Since at the corners *c* and *d* the angles formed by the mitered faces are on lines which diverge inwardly I employ a different form of lock at

these points, whereas the tongues and grooves first described at corners *a* and *b* are shaped with reference to the pivotal action of the side pieces occurring at the meeting points at the inner ends of the miters the tongues and grooves at the corners *c* and *d* are shaped with reference to the outer points of these miters. Consequently at the bases of miter faces 9 and 12 I cut an ogee shaped face 18 the outer point 19 of which projects slightly beyond the mitered face while its inner end terminates at and defines the inner edge of a plane 20 well within the plane of the mitered surface. Midway of this plane 20 a groove 21 is cut. To fit the recesses thus formed there are formed on the complementary mitered faces 10 and 11 a corresponding stepped projection 22 carrying a tongue 23 and having an ogee curved face 24, the inner edge of which forms a shoulder 25. The proportion of these parts is such that when the box or drawer side pieces are adjusted from the rhomboid shown in Fig. 2 to the rectangular position of Fig. 1, the bringing together of the mitered faces will also cause the tongues 23 to fit within the grooves 21. This movement of the parts also brings into engagement the similarly shaped ogee surfaces, the overlapping parts of which prevent the separation of the box side pieces in one direction while the interfitted tongues and grooves prevent their being pulled apart in the other direction.

In accomplishing the foregoing interfitting of the parts it is realized first that the parts being of wood, when the outer corners of the notches 21 and 23 engage they will each yield sufficiently to interlock without chipping even if the pivotal action about the outer corners *c* and *d* is alone depended upon. However, what may actually happen and probably does occur in the many instances, as I have demonstrated in practice by making the joints illustrated of metal, is that when the tongue 23 engages the surface 20 at the proximate corner of the groove 21 the portion 11 of the miter moves slightly along the miter portion 12 until the lower point of the ogee 24 engages the ogee 18. At such time the relative angular position of the side pieces 2-3 and 1-4 are so nearly at right angles to each other that the parts readily slip into their position of final engagement. Even though the interfitting of the above parts and also the positioning of the projections 17 in the grooves beneath the tongues 14 is accomplished as a result of the yielding of the wood fibers no damage results as the interlocking has been accomplished and it is not contemplated that the joints will ever be opened.

It will be seen from the foregoing that I have provided a means for connecting the four sides of a box or drawer whereby it may be assembled without the use of tools or templates, its final shape being assured by the complementary construction of the corner joints, the rectangular assembly being maintained by the bottom 26 which is subsequently attached to the lower edges of the side pieces, in the case of a drawer, or by both the top and bottom closures affixed thereto in the case of a box. The closely fitting parts of the several joints may if desired also be firmly united by the application of cement or glue to the surfaces before they are united, as will be understood.

Both of the joints above described may be used in pairs in the construction of furniture drawers, as shown in Figs. 4 and 5, for connecting side

pieces to a drawer front. For example I have shown in Fig. 4 a drawer front 30 and side pieces 31-32 provided respectively with the tongues and grooves employed at the corners *a* and *b* of Figs. 1 and 2. These are brought into interlocking engagement by positioning the side pieces first in the dotted line position and rotating their free ends outwardly at right angles to the front piece 30. Again in Fig. 5 I have shown the joint construction used at the corners *c* and *d* of Figs. 1 and 2 forming the framing connections between the ends of a drawer front 35 and the side pieces 36-37 which are interengaged by swinging the free ends of the side pieces from the dotted line position to that shown by the full lines.

In both of these assemblages the free ends of the side pieces are connected at their rear or free ends by a back piece 40 which may be mortised or otherwise attached to them as shown in Fig. 6. It will also be understood that in these constructions the drawers are provided with a bottom which is subsequently attached and corresponds to the part indicated by 26 in Fig. 3.

I claim:

1. A knockdown box comprising four side pieces having mitered end faces, two of which when said pieces are assembled in the form of a rhomboid engage at their inner points and two engage at their outer points, said inner engaging faces being provided respectively with tongues and grooves having curved surfaces shaped to form cooperating undercuts and shoulders, said outer point engaging faces being respectively provided with lateral stepped undercuts provided with grooves and similar projections provided with tongues, the several tongues and grooves on the several faces being formed to interlock upon relative rotative movement of the parts to bring them into rectangular form.

2. A knockdown box comprising four side pieces having end faces which unite to form a rectangular structure, the end faces of one pair of diagonally opposite corners being provided respectively with tongue and grooves having curved surfaces shaped to form cooperating undercuts and shoulders, the faces of the other pair of diagonally opposite corners being respectively provided with lateral stepped undercuts provided with grooves and similar projections provided with tongues, the several tongues and grooves on the several faces being formed to interlock upon relative movement of the side pieces from a rhomboidal position of assembly into a rectangular position.
